SPRINKLER

Ruth H. Ficken, Sherwood, Oreg.

Application December 26, 1951, Serial No. 17,831

Term of patent 14 years

(Cl. D91—1)

To all whom it may concern:

Be it known that I, Ruth H. Ficken, a citizen of the United States, residing at Sherwood, in the county of Washington and State of Oregon, have invented a new, original, and ornamental Design for Sprinkler, of which the following is a specification, reference being had to the accompanying drawing, forming part thereof.

I claim:

The ornamental design for a sprinkler, as shown.

RUTH H. FICKEN.
